UNITED STATES PATENT OFFICE.

MYRTLE A. JOSLIN, OF GRAND RAPIDS, MICHIGAN.

DESIGN FOR A PAN.

47,536.

Specification for Design.

Patented July 6, 1915.

Application filed February 25, 1915. Serial No. 10,639. Term of patent 14 years.

To all whom it may concern:

Be it known that I, MYRTLE A. JOSLIN, a citizen of the United States of America, residing at Grand Rapids, in the county of Kent and State of Michigan, have invented a new, original, and ornamental Design for Pans, of which the following is a specification, reference being had to the accompanying drawing, forming part hereof.

In the drawings: Figures 1 and 2 are

perspective views of a pan, showing my new design and looking at opposite sides of the same.

I claim:

The ornamental design for a pan, as shown.

MYRTLE A. JOSLIN. [L. S.]

Witnesses:

J. H. PALIN,
RALPH L. SEEKINS.
